(57) **CLAIM**

The ornamental design for model vehicle hood vents as shown and described.

DESCRIPTION

FIG. 1 is an upper, left, front perspective view, to include the mirror image, of a model vehicle hood vent showing our new design;

FIG. 2 is an upper, right, rear perspective view thereof;

FIG. 3 is a lower, right, front perspective view thereof;

FIG. 4 is a lower, left, rear perspective view thereof;

FIG. 5 is a front elevation view thereof;

FIG. 6 is a rear elevation view thereof;

FIG. 7 is an upper plan view thereof;

FIG. 8 is a lower plan view thereof;

FIG. 9 is a right side elevation view thereof; and,

FIG. 10 is a left side elevation view of the model vehicle hood vent.

In the drawings, the broken lines illustrate portions of the model vehicle hood vent that form no part of the claimed design. Additionally, only the first embodiment of the model vehicle hood vent is shown. The second embodiment of the claimed design is a right model vehicle hood vent which is a mirror image of the left model vehicle hood vent disclosed in the first embodiment.
